BOTTLE OPENER AND CAP SEALER

Harden McFarland, Vallejo, Calif.

Application July 24, 1950, Serial No. 11,368

Term of patent 14 years

(Cl. D44—29)

To all whom it may concern:

Be it known that I, Harden McFarland, a citizen of the United States, residing at 617 Sacramento Street, Vallejo, State of California, have invented a new, original, and ornamental Design for Bottle Opener and Cap Sealer, of which the following is a specification, reference being had to the accompanying drawing, forming a part hereof:

Fig. 1 is a top plan view of a "Bottle Opener and Cap Sealer" showing my new design.

Fig. 2 is a side elevational view of the device of Fig. 1.

Fig. 3 is a side elevational view of the device of Fig. 1 taken at right angles to the view of Fig. 2.

Fig. 4 is a bottom plan view of the device of Fig. 1.

Fig. 5 is a vertical cross-sectional view of the device of Fig. 1.

Fig. 6 is a perspective view of the device of Fig. 1.

I claim:

The ornamental design for a bottle opener and cap sealer, as shown.

HARDEN McFARLAND.
